TO THE MARBLE CLIFF QUARRIES COMPANY, OF COLUMBUS, OHIO, A CORPORATION
OF OHIO

HOPPER FEEDING DEVICE

Application filed December 23, 1926. Serial No. 156,701.

Our invention relates to hopper feeding devices, particularly of the rotary type.

In the art the use of hopper feeding devices consisting of a cylindrical casing 5 within which a shaft having compartment pockets formed as segments of the cylindrical casing, are old and well known. Our invention employs as a mechanical feeder a rotary shaft carrying a set of segment shaped compartments, each one of which feeds material from a receiving side of a casing to a discharge side. The improvements which we have made relate more to the clearance which is provided in the casing, to the method of regulating the flow of material to the rotary feeder, and to the position into which the material to be fed is exposed to the compartment pockets, than to any invention inherent in the shape of the rotary feeder.

It is the object of our invention to provide, for conducting such materials, as crushed stone, lime, ore and other kinds of powdered, granulated or semi-plastic material, a leak-proof feeding device which will effectively resist blocking by nails, spikes and other foreign material which we have found to be a constant source of trouble with other types of feeders.

Referring to the drawings in which we have illustrated a preferred assembly:—

Figure 1 is a side elevation of the feeder.

Figure 2 is an end elevation of the assembly shown in Figure 1.

Figure 3 is a perspective view of the internal compartment feeder.

Figure 4 is a sectional view taken along the lines 4—4 in Figure 1.

The casing which is generally indicated at 1 may be of desired shape, providing it has a compartment such as is indicated at 2 therein. The casing which we have shown has a flanged portion 3 for attachment to a feeding chute, and a flanged portion 4 for attachment to a delivery chute. The casing has side walls 5 which we have shown with orifices 6 over which plates 7 may be riveted or welded. The plates 7 are preferably mounted on the outside of the side walls 5, so that an annular recess is provided for housing the rotary

feeding device. The feeding device is composed of a central rotatable axial shaft 8 which may be squared to engage a squared orifice 9 extending through the rotor. The rotor has a central hub portion 10 with disc-like sides 11 which fit within the recess in the casing, so that no capacity of the compartment pockets 12 will be wasted, and so that there will be no opportunity for leakage, and so that no annular spaces will be formed which would be likely to trap foreign matter passing through the feeder, and thus block its operation. Blades 13 extending radially from the central hub, form the compartment pockets.

The rotor vanes 13 are of such length that a very small opening 14 is left between the outer edge of each blade and the bottom wall 2a of the compartment 2. The casing at the top, however, provides considerable clearance, so that material carried in the pockets is not likely to strike the upper wall of the casing. In order to better illustrate the principle involved, we have shown an opening 15 in the top wall of the casing. We will ordinarily provide a cover for this opening, but such a cover is not essential to the operation of the feeder. Extending preferably in approximately the position shown in Figure 1, we have indicated a deflecting plate 16 which may be moved laterally into the lower compartment 2.

In Figure 1 we have indicated the position in which crushed stone or lime will appear in the feeder casing. We have indicated the compartments of the feeder by the letters a, b, c, and d respectively, beginning at the start of the filling operation. The direction of rotation of the feeder is counterclockwise. The compartment a will not fill during its first quarter revolution, the material being pushed away from the hopper by the vane 13. The compartment b in the position shown in Figure 1 is in the filling position. By regulating the gate 16, the supply in the compartment in the filling position may be quite accurately controlled. The amount, however, which is carried over into the compartment c is not limited by the upper casing wall, as ample clearance is provided. The

compartment *d* is empty having discharged its load by gravity into the discharge portion of the casing.

While we have shown a rotor having four compartments, it will be immaterial if a greater or lesser number of compartments is provided. In some feeders of the same general type, it is possible to regulate the amount fed by the capacity of the compartment, as the feeder is limited by the upper casing wall, making a fairly tight joint with the vanes of the rotor. In our novel type the capacity can be controlled by measuring or weighing the amount which comes over in each compartment with the gate at a certain position. Then by calibrating the gate as indicated at 16*a*, a measured quantity may be fed, depending somewhat on the column of the supply held back by the gate 16.

Having thus described our invention, what we claim as new and desire to secure by Letters Patent, is:—

A feeding device comprising a casing with offset side walls for seating the sides of a feeding device, and a feeding device rotatably mounted in said casing, said device having disc-like sides with a hub extending across between said sides, and vanes extending radially from said hub subdividing said device into feeding compartments, said disc-like sides extending into said offset side walls, and said casing forming a seal against the outer edges of vanes in the lowermost position thereof, and having clearance at the uppermost position of the vanes, and a plate extending diagonally into said casing tangentially to the periphery of said disc-like sides for diverting material from a direct gravity drop into said compartments, said plate being extendible to carry material within said casing and into a compartment therein having a bottom extending substantially in horizontal alignment with the lowermost portion of said feeding device.
